UNITED STATES PATENT OFFICE.

JOHN T. H. PAUL, OF CHICAGO, ILLINOIS, ASSIGNOR TO E. GOLDMAN & COMPANY,
INCORPORATED, OF CHICAGO, ILLINOIS, A CORPORATION OF ILLINOIS.

BOTTLE-CARRIER.

1,013,051.

Specification of Letters Patent. Patented Dec. 26, 1911.

Application filed March 22, 1911. Serial No. 616,217.

To all whom it may concern:

Be it known that I, JOHN T. H. PAUL, a citizen of the United States, residing at Chicago, in the county of Cook and State of Illinois, have invented a new and useful Improvement in Bottle-Carriers, of which the following is a specification.

My invention relates to an improvement in the construction of carriers for supporting in inverted position bottles on a conveyer traversing cleansing means in a machine for washing the bottles and soaking off their labels. Such a machine forms the subject of my pending application for Letters Patent Serial No. 579,470, filed August 29, 1910; and I have devised my present improvement more particularly for use therein to attain the advantages hereinafter pointed out.

20 In the accompanying drawings, Figure 1 is a broken section on line 1, Fig. 2, illustrating so much of my aforesaid machine as is necessary to show the operative connection of my improved bottle-carrier; Fig. 25 2 is a broken sectional plan view of the showing in Fig. 1, but without the bottles in the carrier and the stop-shield over the path of the bottles; Fig. 3 is a section on line 3, Fig. 2, and Fig. 4 is a section on the irregular line 4—4, Fig. 1.

The base of my improved carrier is formed of two parallel bars 5, 5 secured together by spacing-members 6 at intervals and embracing at their opposite ends similar metal blocks 7, 7 provided with forward and rear recessed faces 8 and 9 and having arms 10 extending perpendicularly from them and terminating in perforate heads 11 which project outwardly at right angles to the arms. A frame 12, comprising a pair of diverging side-members 13, 13 connected by a cross-member 14 with eyes 15, 15 at the junctions, embraces each block 7 at the converging relatively-wide ends of the members 45 13, where they are let into the recessed faces, and they and the blocks are rigidly secured to the bars by bolts 16 passed through them. Only one end of the carrier is illustrated in the drawings, but both ends, as will be understood, are similarly equipped with the recessed arm-carrying blocks and frames 12. The two end-frames 12 are connected at their eyes 15 by parallel reinforcing-rods 17 and 18, which may be riveted at their 50 projecting ends, and which assist in stay-

ing peculiar bottle-pockets 19, as hereinafter explained. These pockets are all alike, each being formed of two similar sections. Each section is a casting consisting of an arc-shaped, approximately semi-circular band 60 20 terminating at one end in an eye 21 and having bulging ribs 22 extending from one-half of the arc and converging to a head 23 presenting an internally rounded surface, with a leg 24 projecting from its outer 65 end; and from the outer face of the rib 22, diametrically opposite the eye 21, projects similarly an eye 21¹. To form a pocket 19, two of the sections are arranged between the bars 5 with corresponding ends 70 of their bands 20 in meeting relation, and their legs are bolted to the inner face of a base-bar 5. In this way a series of the pockets is provided on the carrier-base with the successive bands 20 in abutting relation to each other, thereby bringing their eyes 21 into alinement for passing the rod 18 through all of them and their eyes 21¹ into alinement for passing through them the rod 17, when, with the ends of the rods 75 20 projecting through the frame-eyes 15 their ends may be riveted, as hereinbefore mentioned. Similar nozzle-devices 25, one for each pocket, are supported on the carrier-base. Each of these devices is a casting 80 consisting of a hollow head 26 tapering externally at one end from which a jet-tube 27 extends, the head having four wings 28 projecting from its tapering end to surround the tube and provided with notches 85 29 in their free ends to afford a seat about the tube for the neck-end of an inverted bottle 30; and two of the wings are formed with lateral perforated extensions or feet 31, through which to rivet the nozzle-devices 90 95 to the inner face of the bar 5 to which the pockets are bolted. The positions of the nozzle-devices relative to the pockets is such as to register the tubes 27 with the centers of the ring-like outer ends of the pockets. 100

As explained in my aforesaid application, the tank (not herein shown) has sets of jet-pipes 32 supported to extend across it at intervals for jetting the washing liquid contained in the tank into and against the outer 105 surfaces of bottles presented to them intermittently in inverted position. It is for handling the bottles, and particularly those equipped with so-called "patent" stoppers 33 (Figs. 1 and 3), to better advantage in 110

the machine that I have devised my present improved carrier. A track, one rail of which is represented at 34, is supported to extend lengthwise about the tank, and upon these 5 rails endless chains, a portion of one of which is shown at 35, are caused to travel intermittently, the chains carrying rollers 36 at intervals to ride on the track. Corresponding links of the chains have perforated 10 ears 37 extending inwardly from them for riveting thereto, as represented at 38 in Fig. 1, the heads 11 of the carriers, whereby the latter are disposed on chains of the conveyer, which they form, at uniform intervals 15 apart to adapt them to present the inverted bottles with which they are loaded, and the nozzle-devices 25 to successive sets of the jets on the pipes 32 by each intermittent movement of the conveyer. A shield 39 extends 20 over the path of the bottles above the tank to afford a stop to the bottles and deflect water from the nozzles back into the tank.

The more important objects of my improvement in the construction of the carrier are to render it simple and strong and adapt the pockets to guide to their seats about the tubes 28 the bottle-necks smoothly without breaking them; while the open or 25 ribless side of the pocket peculiarly adapts it for bottles provided with the "patent" stoppers referred to, since it is devoid of any obstruction that would tend to catch the porcelain stopper in removing from the 30 pocket a bottle provided therewith.

What I claim as new and desire to secure by Letters Patent is—

1. A bottle-carrier for the purpose set forth, comprising, in combination, a base 40 provided on its ends with means for connecting it with conveyer-chains, a series of bottle-pockets secured to the base, each composed of sections consisting of arc-shaped bands provided with eyes on their opposite 45 ends, internally-rounded heads and spaced bulging ribs converging toward the heads and connecting therewith said bands, said pockets being open on one side of the car-

rier, rods extending through the ears on opposite sides of the bands and connecting 50 the pocket-forming sections together, and nozzle-devices secured to the base to register centrally with the pockets and provided with bottle-neck seats.

2. A bottle-carrier for the purpose set forth, comprising, in combination, a base formed of parallel spaced bars with blocks and frames secured between them at their ends, and arms on the blocks by which to connect the carrier with conveyer-chains, a 60 series of bottle-pockets formed of sections extending from between said bars and provided on their outer ends with eyes, said pockets being open on one side of the carrier, rods connecting said frames along opposite sides of the pocket-series and passing through said eyes to connect the pocket-forming sections, and nozzle-devices secured to the base to extend from between the bars thereof in central registration with the pockets and provided with bottle-neck seats. 65

3. A bottle-carrier for the purpose set forth, comprising, in combination, a base formed of parallel spaced bars and provided on its ends with means for connecting the carrier 75 with conveyer-chains, frames on the ends of said base, a series of bottle-pockets each composed of sections consisting of outer arc-shaped bands provided with eyes on their opposite ends, inner heads and spaced bulging ribs converging toward the heads and connecting therewith the bands, and feet on the heads at which said sections are secured to the inner face of a base-bar, said pockets being wholly open on one side of the carrier, 80 rods connecting said frames along opposite sides of the pocket-series and passing through said eyes to connect the pocket-forming sections, and nozzle-devices secured to the inner face of a base-bar to extend in 85 central registration with the pockets and provided with bottle-neck seats.

JOHN T. H. PAUL.
